APPARATUS FOR MAKING PIEZOELECTRIC CRYSTALS

Hal F. Fruth, Chicago, Ill., assignor to Galvin Manufacturing Corporation, Chicago, Ill., a corporation of Illinois

Application April 24, 1944, Serial No. 532,430

3 Claims. (CL 51—124)

1

The present invention relates to improved apparatus for manufacturing piezoelectric crystals, and more particularly, to improved apparatus for grinding the faces of piezoelectric crystals to impart predetermined frequency characteristics thereto.

In the manufacture of piezoelectric crystals, such, for example, as quartz crystals adapted for use in communication circuits, and more particularly, for use in crystal microphones, radio transmitting and receiving systems, and the like, the crystal blanks are first cut from the crystal stock and are then ground to the dimensions required to provide the desired frequency and activity characteristics. More particularly, the usual crystal blank is cut in the form of a wafer-like rectangular piece, having dimensions slightly larger than the desired dimensions, is then reduced in size to approach the desired rectangular dimensions by the use of lap and edge grinding apparatus, and finally is reduced to the exact desired dimensions by finish grinding operations.

It is an object of the present invention to provide improved grinding apparatus for rapidly grinding the faces of a crystal to render the faces substantially flat and substantially parallel, without the production of deep scratches or other surface irregularities therein.

It is another object of the invention to provide improved lap grinding apparatus which may be easily loaded with a plurality of crystal blanks and in which the contact pressures used in grinding the different crystals may be determined on an individual crystal basis.

The invention, both as to its organization and method of operation, together with further objects and advantages thereof will best be understood by reference to the following specification taken in connection with the accompanying drawing, in which:

Fig. 1 is a top perspective view illustrating improved lap grinding apparatus characterized by certain features of the present invention and utilized in part in the practice of the present improved methods;

Fig. 2 is a side view of the apparatus shown in Fig. 1; and

Fig. 3 is a fragmentary sectional view illustrating the arrangement of the weights which are individually utilized to maintain the crystals in engagement with the abrasive surface of the apparatus shown in Figs. 1 and 2.

In using the present improved apparatus, the crystal wafers or blanks are obtained by sawing thin slabs from the crystal stock and by dicing

each slab into rectangular blanks of the approximate desired dimensions, all three dimensions of each blank being considerably greater than the desired dimensions in order to permit the grinding operations to be carried out. The rough cut crystal blanks are next placed in the lap grinding apparatus shown in Figs. 1, 2 and 3 of the drawing, and subjected to a lap grinding operation for a definite interval of time sufficient to insure that one face of each crystal will be ground exactly flat. After one face of each crystal has been thus ground to impart a flat contour thereto, belt grinding apparatus is used to pressure grind the opposite face of each crystal for the purpose of reducing the thickness of the crystal. Following this operation, which is utilized to reduce the thickness of each crystal more nearly to approach the desired thickness with considerable grinding rapidity, the crystal blanks are returned to the lap grinding apparatus and both face surfaces of each crystal are ground in this apparatus in order to remove deep scratches and pits from the crystal faces and to further reduce the thickness of each crystal more nearly to approach the desired thickness. In this regard, it will be understood that the thickness of each crystal determines its resonant frequency, the whole object of the face grinding step being that of reducing the thickness of the crystal to the exact desired thickness in order to impart a predetermined resonant frequency to the crystal, while at the same time obtaining a highly polished and scratch-free surface. In other words, the thickness of each crystal may be measured in terms of the resonant frequency of the crystal. During the third described step of lap grinding the crystal faces, the crystals are ground until the resonant frequency of each crystal is from ten to sixty kilocycles lower than the particular desired resonant frequency, in preparation for finish grinding to the exact desired frequency.

Referring now more particularly to the structural arrangement of the lap grinding apparatus illustrated in Figs. 1, 2 and 3 of the drawing, this apparatus comprises a circular plate 10 which is rigidly mounted at the upper end of a shaft 12 for rotation about its center, and is provided with a flat upper abrading surface 10b. The shaft 12 is journaled for rotation in bearing members 13 which are mounted upon opposite sides of a supporting platform 11. This platform is held in elevated position above a base, not shown, by means of side members, one of which is indicated at 11a, and the shaft 12 is adapted to be rotated by means of an electric motor carried by the base. The

platform 11 also supports stationary members 14 and 15 having circular edges 14a and 15a which embrace but do not touch opposite peripheral arcs of the plate 10. These stationary members are held in elevated positions above the platform 11, such that the top surfaces thereof are exactly flush with the top abrading surface of the plate 10, by means of supporting posts 16 which are anchored to the top of the platform 11 in any suitable manner.

Circular crystal holding plates 18 and 19, each provided with a plurality of crystal receiving pockets 22 and 23, are utilized to support the crystals in engagement with the top abrasive surface 10b of the plate 10. More specifically, these holders are rotatably supported at the ends 17a and 17b of a bifurcated arm 17, pivot pins 20 and 21 being utilized to rotatably mount the plates 18 and 19 at the ends of the two arm bifurcations. The arm 17 is pivotally mounted at the upper end of a post 24 extending upright from the platform 11 and rigidly anchored thereto by means of mounting screws 25. For the purpose of pivoting the arm 17 back and forth through a predetermined angle, thereby to sweep the crystal holders 18 and 19 back and forth through a limited arc which overlies the abrasive upper surface 10b of the plate 10, this arm is connected to a rotatable crank plate 26 through a pin and slot connection which comprises a pin 29 extending upwardly from the plate 26 within a slot 29a formed longitudinally of the arm. The plate 26 is set screw mounted upon the upper end of a second rotatable shaft 27 which is journaled intermediate the ends thereof within bearing members 28 disposed upon opposite sides of the platform 11, and is driven at a slow speed either through a speed reducing gear box actuated by the driving motor for the shaft 12 or by a second slow speed electric motor directly connected to the shaft 27 and carried by the base located at the bottom ends of the side members 11a.

Briefly to consider the operation of the described lapping apparatus, it may be pointed out that before rotation of the shaft 12 to drive the abrading plate 10 and rotation of the shaft 27 to pivot the arm 17 back and forth are initiated, a crystal 9 is placed in each or a portion of the pockets 22 and 23 respectively provided in the two holders 18 and 19. Depending upon the position of the arm 17, each crystal is disposed face downwardly against the upper surface of one of the two stationary members 14 and 15 or the upper abrading surface 10b of the plate 10. In this regard it is noted that the abrading surface 10b of the plate 10 is ground perfectly flat, that the upper surfaces of the two members 14 and 15 are likewise perfectly flat and are exactly flush with the surface 10b of the plate 10. Weights in the form of liquid filled rubber cups 30 are utilized to establish the desired contact pressure between the bottom surface of each crystal 9 and the upper surface of the member 10, 14 or 15 against which the particular crystal bears. More specifically, each partially filled liquid receiving cup 30 determines the contact pressure between the lower face of the crystal which it weights and the upper abrasive surface 10b of the plate 10. Each cup 30 loosely fits within its associated pocket 22 or 23 and is provided with relatively heavy sidewall portion 30a to prevent expansion of the sidewall into binding engagement with the walls of the pocket. Each cup is also provided with a thin, flexible bottom wall 30b in order that a distributed pressure over the entire upper surface of the as-

sociated crystal 9 may be produced by the liquid 31 with which the cup is partially filled. Any liquid, such, for example, as mercury, having great weight per unit volume, may be utilized in filling the cups 30 to the level required to establish the desired contact pressure. After the pockets of the holders 18 and 19 have been loaded in the manner just explained, the abrading surface 10b of the plate 10 may be sprinkled with diamond dust or another loose abrasive of suitable fineness, following which operation of the driving motor or motors to rotate the two shafts 12 and 27 may be initiated.

In response to rotation of the shaft 27 the arm 17 is pivoted back and forth about the pivot pin 24 through a limited angle by means of the pin and slot connection between this arm and the plate 26. As a result, the crystal holders 18 and 19 are moved back and forth across the center of the plate 10, so that peripheral portions thereof alternately overlap the two stationary members 14 and 15. Incident to this movement of the crystal holders, each crystal is moved across the abrading surface 10b from one side of the center of rotation of the plate 10 to the other, with the result that the lower surfaces of the crystals are rapidly abraded. During movement of the arm 17 from one limit of its range of movement to the other, each of the two crystal holders 18 and 19 is rotated relative to the plate 10 in order to change the position of each crystal relative to the abrasive surface 10b of the plate 10. Thus assuming that the plate 10 is rotating in a counter-clockwise direction, as viewed in Fig. 1 of the drawing, and that the crystal holder 19, for example, occupies the position shown in full lines in this figure of the drawing, the frictional engagement between the abrading surface 10b of the plate 10 and the engaging faces of the crystals within the pockets 23 of the holder causes the holder to be rotated in a counter-clockwise direction, such that the positions of the crystals relative to the abrading surface are continuously changed. As the holder 19 is moved from this position to a position wherein the center of the holder substantially overlies the center of the plate 10, the rotational forces acting upon this holder are more effectively utilized to cut down the degree of slip between the plate 10 and the holder, with the result that the speed of rotation of the holder is increased. During continued movement of the holder 19 towards the stationary member 15 and away from the center of the plate 10 the forces tending to rotate this holder are less effectively utilized with the result that the speed of rotation of the holder relative to the plate 10 is decreased. This decrease in the speed of rotation of the holder 19 as the holder is moved towards the edge of the plate 10 is accompanied by an increase in the linear speed at which the abrasive surface 10b underlying the crystal faces is moved relative to these faces. Thus it will be apparent that the rate of abrasion is increased as the holder 19 is moved towards the edge of the plate 10. During continued movement of the holder 19 in the indicated direction, a point is reached at which the edge portion of the holder engages the edge of the stationary member 15. When this occurs and due to the frictional drag between the engaging surfaces of the parts 15 and 19, the direction of rotation of the holder 19 about its pivot point 21 is reversed. As the degree of overlap between the two parts 15 and 19 is increased, the resultant of the rotational forces acting upon

the holder 19 is shifted in a direction to increase the speed of rotation of the holder 19 about its pivot point 21 in the reversed direction. Thus it will be apparent that the speed of rotation of the holder 19 is substantially constantly changed during movement of this holder from its illustrated full line position to its illustrated dotted line position. During movement of the arm 17 in the reverse direction, the action is the reverse of that just described. As each crystal 9 within a pocket 23 of the holder 19 is moved to a position where the lower face thereof partially overlies and engages the abrading surface 10b and partially overlies and engages the upper surface of the stationary member 15, the frictional forces acting thereon tend to rotate the crystal within the pocket 23 in which it is disposed. Rotation of the crystal within its pocket is permitted due to the loose interfitting relationship between the side walls 30a of the rubber cup 30 and the walls of the pocket. Thus each crystal is not only rotated about the axis 21 of the holder 19, but is also rotated about its own center during each movement of the arm 17 from one limit of its range of pivotal movement to the other.

From the foregoing explanation it will be understood that due to the rotation of each crystal 9 in a plane parallel to the surfaces of the parts 14, 15 and 10, the edge sector of the crystal initially engaged by the rotating abrasive surface 10b of the plate 10 is continuously changed in a more or less random manner with the result that the direction of cut across the crystal face is continuously shifted at random. The same action of rotating each crystal disposed within a pocket 22 of the holder 18 about two different centers of rotation during back and forth movement of this holder between the limits of its range of movement, is also obtained during the back and forth pivotal movement of the arm 17. The purpose of thus continuously changing the edge sector of each crystal which is initially engaged by the abrasive surface is that of preventing scratches from being formed in the crystal face being abraded, due to recurrent movement of the same abrasive particles along the same lines of abrasion across the crystal face. Thus it is possible with the described apparatus to obtain relatively rapid grinding of the crystal faces to a substantially flat contour without producing scratches or other surface marks in the abraded crystal faces. Moreover, by the system of individual weights comprising the cups 30 filled to the same or different liquid levels, either uniform or non-uniform grinding of the different crystals may be obtained, as desired.

While one embodiment of the invention has been described, it will be understood that various modifications may be made therein which are within the true spirit and scope of the invention as defined in the appended claims.

I claim:

1. Apparatus for face grinding piezoelectric crystals, comprising a circular abrading plate rotatable about its center and having a flat upper abrading surface, a stationary member having a top surface flush with the upper surface of said plate and having an edge closely adjacent at least a portion of the periphery of said plate, an arm pivotally movable about a point removed from the axis of rotation of said surface, a crystal holder pivotally connected to said arm for free rotation relative to said abrading plate, and means for pivoting said arm back and forth through a limited angle which is so related to said abrading plate and stationary member that said holder partially overlies said member each time said arm is moved to one limit of said angle.
2. Apparatus for face grinding piezoelectric crystals, comprising a circular abrading plate rotatable about its center and having a flat upper abrading surface, stationary members having top surfaces flush with the upper surface of said plate and having edges closely adjacent portions of the periphery of said plate upon opposite sides of said plate, a bifurcated arm pivotally movable about a point removed from the center of said abrading plate, crystal holders respectively connected to the bifurcations of said arm for free rotation relative to said abrading plate and said arm, each of said holders including pockets for maintaining crystals face downward against said abrading surface, and means for pivoting said arm back and forth through a limited angle which is so related to said abrading plate that said holders are alternately moved to overlie different ones of said members as said arm is moved from either limit of said angle to the other.
3. Grinding apparatus comprising a circular abrading plate rotatable about its center and having a flat upper abrading surface, a stationary member having a top surface flush with the upper surface of said plate and having an edge closely adjacent at least a portion of the periphery of said plate, a rotatable work holder for holding a work piece in a position offset with respect to the axis of rotation of said work holder and in contact with said abrading surface, means supporting said holder for free rotation about its axis of rotation, and means for so moving said supporting means that said work holder is moved transversely back and forth across said abrading surface and overlies the upper surface of said plate, whereby engagement of the work piece with said abrading surface and the upper surface of said plate rotates said work holder relative to said supporting means and thus changes the line of cut across said work piece.
